Primary Examiner — Selina Sikder(74) *Attorney, Agent, or Firm* — Mark E. Rose; Philip N. Smith; Bridget L. McDonough(57) **CLAIM**

I claim the ornamental design for a tabletop remote load control device, as shown and described.

DESCRIPTION

FIG. 1 is a perspective view of a tabletop remote load control device according to my new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The rear views form no part of the design and are omitted. The broken lines showing the arrows and the light bulb icons are for the purpose of illustrating environmental structure and form no part of the claimed design.
